GRINDING AND POLISHING MACHINE

George D. Moomaw, Syracuse, N. Y., assignor to
Halcomb Steel Company, Syracuse, N. Y., a
corporation of New York

Application December 8, 1931, Serial No. 579,745

7 Claims. (Cl. 51—137)

This invention relates to improvements in grinding and polishing machines in which rotary abrasive tools are simultaneously rotated about the work and moved across the work in surface 5 contact therewith.

In the manufacture of small rods or wire, it is often desirous and sometimes necessary that the finished product has a very smooth and highly polished surface. This result has been 10 very difficult and expensive to obtain with the present known grinding and polishing machines due to the inability of properly controlling the relative surface speed of the abrasive tools and the revolving speed of the tools about the stock. 15 This inability to control the relative speeds of the abrasive tools has necessitated the varying of the speed of the stock or work through the machine in order to obtain a substantially uniform surface finish of stock of varying degrees 20 of hardness or of different grades of material with the consequent sacrifice in time and the quality of workmanship.

The main object of this invention is to produce a grinding and polishing machine of the 25 above mentioned class wherein the relative rotary speed of the abrasive tools about the work and the surface speed of the tools may be readily varied during the operation of the machine.

Another object is to provide a grinding and 30 polishing machine in which a very high surface speed of the abrasive tools may be obtained for the purpose of producing a very high polish upon the work in a minimum of time.

A further object is to produce an apparatus 35 which is sturdy, simple and economical in construction, smooth and accurate in operation, and which may be quickly and easily adjusted for work of different diameters, and all grades of materials.

40 Other objects and advantages relating to the construction and form and relation of the parts thereof will more fully appear from the following description taken in connection with the accompanying drawings in which:

45 Figure 1 is a side elevation of an apparatus embodying the various features of this invention.

Figure 2 is an enlarged face view of one of the 50 revolving tool-supporting disks as viewed from line 2—2, Figure 1.

Figure 3 is a vertical longitudinal sectional view taken substantially in the plane of the line 3—3, Figure 2.

55 Figure 4 is a detail sectional view taken in the plane of the line 4—4, Figure 2.

Figure 5 is a detail sectional view taken on the line 5—5, Figure 5.

Figure 6 is a view similar to Figure 1 illustrating a modified form of my grinding machine.

Figure 7 is an enlarged end view of the machine 5 illustrated in Figure 6 with the lower portion of the standard broken away.

Figure 8 is a detail sectional view taken in the plane of the line 8—8, Figure 7.

Figure 9 is a detail longitudinal sectional view 10 of the work holder taken in the plane of the line 9—9, Figure 8.

Figure 10 is a longitudinal vertical sectional view taken on line 10—10, Figure 7.

Figures 11 and 12 are side elevation and plan 15 views respectively of another modified form of my grinding machine.

Figure 13 is an enlarged front end view viewed from the line 13—13, Figure 11.

Figure 14 is a longitudinal sectional view taken 20 substantially in the plane of the line 14—14, Figure 13.

Figure 15 is a detail transverse sectional view taken on the line 15—15, Figure 14.

As illustrated in the drawings, this device consists of a standard 1 having the lower portion thereof divided to form a pair of legs 2 arranged in spaced relation transversely of the standard 1 and between which is positioned a drive motor 3. 25

This motor 3, as illustrated in Figures 1 and 30 3, has the armature shaft 4 thereof extended outwardly at opposite ends of the motor for driving a pair of tool-supporting disks 5 arranged one at either side of the standard 1.

The motor 3 may be operably connected with the disks 5 in any suitable manner as by belts 6 which pass around the grooved peripheral face of the disks 5 and pulleys 7 secured to the armature shaft 4 in alignment with their respective 40 disks 5.

The disks 5 are secured to respective ends of a horizontally disposed shaft 8 journaled in suitable bearings 9 provided in the upper end of the standard 1.

45 Any suitable means may be employed to maintain the shaft against axial movement such as a pair of axially spaced annular flanges 9' secured to the periphery of the shaft 8 or made integral therewith, and which are adapted to travel in corresponding annular grooves 10 provided in the bearing member 9. This shaft 8 is also provided with an opening 8' extending longitudinally and centrally therethrough for receiving the work as the wire A. 50

Upon each disk 5 is secured a pair of electric motors 12, each of which has the drive shaft 13 thereof extended outwardly from the outer face of the motor for receiving a suitable pulley 14 which is secured to the respective shaft by screws 15, or other suitable means, so as to be rotated thereby.

The motors 12 may be secured to the disk 5 in any well known manner, and for this purpose, 10 each motor is provided with a sectional case 16 adapted to extend through suitable apertures 17 provided in the disks, each section being provided with an outwardly extending annular flange 18 positioned one adjacent either side of the disk 15 and secured thereto by screws or bolts 19.

The motors of each disk are positioned adjacent the edge of the disk at opposite sides thereof, and at one side of a plane passing diametrically through the disk and so arranged that an 20 abrasive belt as 20 extending from one pulley 14 to the other will normally pass through the axis of the disk and, therefore, the axis of the shaft 8.

In order that the outer ends of the shafts 13 25 may be firmly supported, there is provided for each shaft a bracket 21 which is secured at one end to the disk 5 by screws or other means, and has the other end thereof provided with a socket 21' in which is mounted a ball bearing 30 member 22 adapted to receive and rotatably support the outer end of the shaft 13.

A suitable take-up pulley 24 is also employed to maintain a pre-determined tension on the belt 20, and for this purpose, the pulley is adjustably mounted on the disk 5 for movement toward and from the axis of said disk in a radial plane extending midway between the motors 12.

The take-up pulley 24 for each belt 20 is rotatably mounted on a shaft 25 which has the 40 inner end thereof secured to or made integral with a substantially rectangular base plate 26 which is secured by screws 27 to a slide 28 mounted for longitudinal movement upon a radially extending guideway 29 secured to or made integral with the outer face of the disks 5.

In order that the pulley 24 may be readily adjusted, the base plate 26 and slide 28 are provided with a threaded opening 30 in which is screw-threaded a screw 31 which has the outer 50 end thereof extending through and rotatably mounted in an apertured lug 32 provided adjacent the outer end of the guideway 29 as shown more clearly in Figures 2 and 3.

In order that the pulley 24 may be maintained in the adjusted position, there is provided a lock nut 33 screw-threaded on the screw 31 and positioned adjacent the inner face of the lug 32 which co-operates with the head 31' of the screw for clamping said screw to the lug 60 32 and preventing accidental rotation of the screw.

The outer end of the shaft 25, in this instance, is supported by means of a bracket 35 carried by the slide 28 and which is secured to the shaft 25 65 by means of a nut 36 screw-threaded on the outer end to said shaft.

In order that the grinding machine will run smoothly and with a minimum amount of vibration, the abrasive tools comprising the belts 20 70 and the motors 12 and take-up pulley 24 for each disk 5 are arranged in substantially right angles to each other as indicated by full lines, and by dotted lines in Figure 2, the full lines in Figure 2 indicating the abrasive tool and operating members on the adjacent disk 5 while the dotted lines

represent the abrasive tool secured to the disk 5 positioned at the opposite end of the standard 1.

These motors 12 may be of any suitable type or construction adapted to revolve at a uniform constant speed, and for this purpose, I preferably use two pole three-phase 50 to 60 cycle 220 volt alternating current motors which, as is obvious, will run at a constant speed at a given frequency, and in order to change the speed of these motors, it is only necessary to change the frequency of the current supplied to said motors, and in order that this may be readily accomplished, I use a generator G as indicated diametrically in Figure 1 and which is driven by a suitable motor M, the current for which is controlled by a rheostat R 15 positioned in the electric circuit for the motor M. In order that the current may be continuously supplied to the motors 12 during the rotation of the disks 5, I connect the wires as W leading from the generator G with a suitable terminal block T 20 secured to the standard 1 and which, in turn, is connected by wires W' to respective brushes 38 carried by brush-supporting arms 39 secured to the standard 1.

The brushes 38 which, in this instance, are 25 three in number are maintained by the arms 39 in operative engagement with respective collector rings 40 electrically connected with corresponding motors and mounted in spaced relation in the outer periphery of a supporting sleeve 41 composed of rubber or other insulating material, and which is secured to a respective disk 5 by mounting said sleeve on hub 5' of the disk.

The operation of the machine may now be 35 readily understood and which consists of threading the wire A which, as illustrated in Figure 1, may be unwound from a spool B carried on a revolving reel C through a tension block 43 of any suitable construction positioned adjacent the inlet end of the machine, and thence through the opening 8' in the shaft 8 and a guide member 44 positioned adjacent the outlet end of the machine to a take-up drum 45 mounted on a shaft 46, and which may be driven in any suitable manner from a motor 47 as by a belt 48 passing around a pulley 49 on the drive shaft of motor 47 and pulley 50 secured to a shaft 51 which, in turn, is operably connected with the drum 45 by means of a pair of gears 52, one of which is secured to the shaft 51 and the other secured to the shaft 46 in any 50 suitable manner.

It is now obvious that by starting the motor 47, the wire A may be steadily drawn through shaft 8 across the face of the abrading belts 20 at a uniform rate of speed. The motors 3 and 12 may now 55 be started which will cause the disks and abrading belts 20 carried thereby to revolve about the work A in a clockwise direction, as indicated by arrow X which evenly treats the entire circumference of the work at the same time motion is imparted to 60 the driving pulleys 14 by motors 12 which actuates said abrading belts causing them to move in a plane parallel with the disks and in opposite directions across the surface of the wire A, as indicated by arrows Y in Figure 2.

It is also evident that the surface speed of the abrading belts 20 may be controlled at will irrespective of the speed of the disks 5 by varying the frequency of the current supplied to the three-phase belt actuating motors 12 which may be accomplished in any well-known manner as by varying the speed of the generator G, as hereinbefore described.

This ability of minutely controlling the surface speed of the abrading belts and the speed at which 75

they are revolved about the work independently of each other, not only permits the polishing operation to be accomplished in the minimum amount of time, but also enables the maintaining 5 of the finished polished work to a pre-determined size or diameter regardless of any varying degree of temper or of different grades of material of the work which may occur without the necessity of stopping or resetting the machine.

10 It will also be observed that this machine is particularly adapted to grinding and polishing work of very limited sizes or diameters due to the staggered arrangement of the abrading belts 20 which permits each belt to overlap the work any 15 required amount to properly perform their individual work.

The belts 20 may be of the same degree or of different degrees of coarseness and may be caused to exert the same or uneven degrees of 20 pressure upon the work as desired by the proper manipulation of the tension pulleys adjusting screws 31, as previously explained, all of which contributes to the high degree of efficiency of this machine.

25 In the modified form of my grinding and polishing machine illustrated in Figures 6 to 10 inclusive, I employ substantially the same principles of construction and operation used in the machine just described and illustrated in Figures 1 to 5 inclusive with the exception that in place of using abrading belts, I employ abrading wheels as 55, one for each disk 56. The disks 56 are constructed similarly to the disks 5 previously described, except that owing to the use of but 30 one motor 12 on each disk, I provide a suitable counter-weight 53' which may be made integral with or secured to the disks diametrically opposite the respective motor 12. These motors 12 are operated and mounted on the disks 56 in the 35 same manner as shown and described for the abrading belts 20 while the abrading wheels 55 may be secured to the motor shaft as 57 in any suitable manner as by a nut 58 screw-threaded on the shaft and which securely clamps to the shaft, a supporting flanged hub 59 upon which the wheel 55 is frictionally mounted in the usual 40 manner between the hub flange as 59' and a collar 60 secured to the opposite or outer end of the hub.

45 Owing to the relatively small diameter of the abrading wheels 55, I have shown the sides of the hub 55' of each disk 56 adjacent the motor and also the adjacent portion of the drive shaft as 61 cut away as at 62 and 63 respectively so as to permit the motors 12 to be mounted on the disks 56 in such a manner as to bring the periphery of the wheels 55 in the axis of the shaft 61.

50 The central opening as 61' extending longitudinally through the shaft 61 is illustrated as somewhat larger in diameter than the opening 6' in the shaft 6 to permit the passing therethrough of work of larger diameters for which this machine is particularly adapted.

55 In order that the work may be maintained in contact with the periphery of the abrading wheels 55 at a substantially pre-determined uniform degree of pressure as the wheels wear away during the grinding and polishing operation, I employ 60 a work-holder 65 which, in this instance, consists of a supporting bracket 66 L-shaped in cross section and which is secured by bolts or screws 67 to the outer face of the corresponding disk 56 with one leg thereof extending over the corresponding wheel 55 and provided with a centrally

disposed dove-tailed slot 68 in one face thereof in which is slidably mounted a work stop slide 69 and which, in turn, has slidably secured to the outer face thereof, a work-retaining slide 70.

5 The lower end of the work stop slide 69 is adapted to extend below the lower face of the bracket 66 into close proximity to the periphery of the wheel 55, the slide being adjustably clamped to the bracket 66 by means of screws 71 so as to 10 permit the adjustment of the slide relative to said bracket for maintaining the lower end of the slide in proper relation with the periphery of the wheel 55 as said wheel grows smaller in diameter during the grinding operation.

15 In order that the work may be maintained against the periphery of the wheel 55 at a pre-determined degree of pressure, the work-retaining slide 70 is yieldingly pressed downwardly towards the wheel 55 by a spring 72 positioned between the upper end of the retaining slide 70 and a lateral lug 69' provided at the upper end of the work-stop 69, said spring 72 being coiled about an adjusting screw 73 which is screw-threaded in the upper end of the retaining slide 70 and slidably mounted in a suitable aperture 20 provided in the lug 69' and adapted to limit the downward movement of the retaining slide 70 for each adjustment of the work-stop slide 69.

25 In order that work of different diameters may be maintained against the work stop slide 69 and wheel 55 during the grinding and polishing operation, the lower end of the work-retaining slide 70 as the inner edge thereof is beveled as at 79.

30 It may now be clearly understood that with the motors 12 for the grinding wheels 55 constructed similarly to the motors 12 for the belts 20, that the rotation of the abrading wheels 55 may be controlled independently of the movement of the disks 56 in the same manner as shown and described for the belts.

35 In Figures 11 to 15 inclusive are illustrated a still further modified form of my grinding machine in which the abrading belt 20 is driven from a motor as 75, which as shown in Figures 12 and 15, is mounted upon the upper end of the standard 1 at one side thereof. This motor 75 is operably connected with the abrading belt 20 to rotate said belt independently of the movement of the supporting disk 76 by means of an 40 endless belt 77 which passes around a pulley 78 secured to the armature shaft 79 of the motor 75 and a second pulley 80 rotatably mounted upon the disk supporting shaft 81. This second pulley 80 is connected in turn by a pair of belts 82 with a pulley 83 secured to the rear end of a drive 45 shaft 84 for one of the abrading belt-supporting pulleys as 85.

50 The shaft 84 as shown more particularly in Figure 14 is rotatably mounted in a ball bearing 60 member 86 mounted in the disk 76 near the peripheral edge thereof.

55 A second abrading belt pulley 87 is positioned near the opposite peripheral edge of the disk 76 to that at which the pulley 83 is located and is 65 rotatably mounted upon a supporting stud 88 which has the inner end thereof reduced in diameter and extended through an elongated opening 89 provided in the adjacent portion of the disk 76, and is adjustably secured to the disk 76 by means of a nut 90 which is screw threaded on the rear end of the stud 88.

60 It will be noted by referring to Figure 13 that the pulley 87 is so positioned relatively to the pulley 83 that the belt in passing from the pulley 75

87 to the pulley 85 will normally pass through the axis of the disk 76 in the same manner as described for the belt 20 in the device shown in Figure 1, and the tension of the belt 20 illustrated in Figures 11 to 15 inclusive may be varied as desired by the proper adjustment of the stud 88 upon the disk 76.

The pulley 85 for driving the abrading belt 20 may be driven in the same direction as the disk 76 or may, as indicated by the arrow 2 in Figure 13, be driven in the opposite direction to that of the disk 76, and for this reason, the pulley 80 may be provided as shown in Figures 14 and 15 with the bearing 80' composed of bronze or other suitable material and which is adapted to rotate on the shaft 81.

Although I have shown but one abrading belt 20 in the device shown in Figures 11 to 15 inclusive, it is evident that a second belt may be employed at the opposite side of the standard 1 as illustrated in Figures 1 and 6 and that this second belt may be operated in the same manner as described, and shown for the single belt by extending the drive shaft 81 beyond the standard 1, and also by extending the armature shaft 79 at the opposite side of the motor 75.

It is also obvious that other changes in the construction both in the form and the relation of the parts thereof of the various forms of my invention may readily be made without departing from the spirit of this invention as set forth in the appended claims.

I claim:

1. In a stock grinding and polishing machine, a hollow shaft, disks mounted on said shaft in longitudinal spaced relation, a revolving abrading tool mounted on each disk, means for rotating said disks and separate means for revolving said tools.

2. In a stock grinding and polishing machine, a standard, a hollow shaft journaled in said standard, a pair of disks mounted on the shaft one adjacent either side of the standard, a revolving abrading tool mounted on each disk, means for rotating the disks and shaft in unison, and separate means for revolving said tools.

3. In a stock grinding and polishing machine, a standard, a hollow shaft journaled in said standard, a pair of disks mounted on the shaft

one adjacent either side of the standard, a revolving abrading tool mounted on each disk, means for rotating the disks and shaft in unison, separate means for revolving said tools in unison and means for varying the speed of the revolving tools.

5

4. In a grinding and polishing machine for small gauge stock, a pair of rotating disks, an electric motor mounted on each disk at one side of the axis thereof, an abrading wheel secured to each motor shaft to rotate therewith, means for rotating the disks and separate means for rotating said motors in unison, an axial passage through the disks of relatively greater diameter than the stock and work holding means associated with each wheel adapted to move the stock transversely through the passage for maintaining the stock in contact therewith at a predetermined pressure as the wheels wear away.

10

5. In a machine for grinding and polishing the outer circumference of stock, a pair of longitudinally spaced disks, means for feeding the stock through the center of said disks, an endless abrasive belt mounted on each of said disks in a position such that the belts are at right angles to each other and in contact with the stock, means for rotating said belts, and means for rotating said disks independently of the means for rotating said belts.

15

6. In a machine for grinding and polishing the outer circumference of stock, a pair of longitudinally spaced disks, means for feeding the stock through the center of said disks, an endless abrasive belt mounted on each of said disks in a position such that the belts are at right angles to each other, means for rotating said belts in different directions, and means for rotating said disks independently of the means for rotating said belts.

20

7. In a machine for grinding and polishing the outer circumference of stock, a rotatable disk, means for rotating said disk, an abrasive member, a motor for driving said abrasive member, and means for mounting said motor on said disk so that the weight thereof is substantially equally distributed on opposite sides of a diametrical axis of the disk.
